(57) **CLAIM**

The ornamental design for a base station for cell phone, telephone handset, and speaker phone, as shown and described.

DESCRIPTION

FIG. 1 is a front and side perspective view of a base station for cell phone, telephone handset, and speaker phone according to my design, wherein the cell phone, handset, and a cord between the handset and base station, as shown by phantom lines, do not form a part of the design, and the cell phone and handset are shown in situ on the base station; FIG. 2 is a front and side perspective view of the base station for cell phone, telephone handset, and speaker phone according to my design of FIG. 1, wherein the cell phone and handset are removed from the base station, and the handset and cord between the base station are shown by phantom lines and do not form a part of the design, and the handset is shown to the right side of the base station; FIG. 3 is a front and side perspective view of the base station of FIG. 1; FIG. 4 is a top view of the base station of FIG. 1; FIG. 5 is a front view of the base station of FIG. 1; FIG. 6 is a right side view of the base station of FIG. 1; FIG. 7 is a left side view of the base station of FIG. 1; FIG. 8 is a back view of the base station of FIG. 1; and, FIG. 9 is a bottom view of the base station of FIG. 1.
